UNITED STATES PATENT OFFICE.

CONRAD BUDKE, JR., OF ST. LOUIS, MISSOURI.

ELECTRIC SIGNAL.

SPECIFICATION forming part of Letters Patent No. 692,423, dated February 4, 1902.

Application filed October 7, 1901. Serial No. 77,900. (No model.)

To all whom it may concern:

Be it known that I, CONRAD BUDKE, Jr., a citizen of the United States, residing at St. Louis, State of Missouri, have invented certain new and useful Improvements in Electric Signals, of which the following is a full, clear, and exact description, reference being had to the accompanying drawings, forming a part hereof.

10 My invention has relation to improvements in electric signals; and it consists in the novel construction and arrangement of parts more fully set forth in the specification and pointed out in the claim.

15 In the drawings, Figure 1 is a general plan of two intersecting trolley systems having my invention applied thereto. Fig. 2 is an elevation thereof. Fig. 3 is a side elevation of the signal device, showing one set of signal-arms raised and the other lowered. Fig. 4 is an end view of Fig. 3. Fig. 5 is an enlarged vertical section on line 5 5 of Fig. 3, with, however, the arms, shown raised therein, dropped to their lowest position. Fig. 6 is an elevation 20 of the solenoids and a section of the box containing them. Fig. 7 is a side view of a section of the trolley-wire with the signal-wire attached. Fig. 8 is an enlarged longitudinal section on line 8 8 of Fig. 9, taken 25 through the spacing-pieces and sleeves, the wires being in elevation. Fig. 9 is a transverse section on line 9 9 of Fig. 7, and Fig. 10 is a section on line 10 10 of Fig. 7 looking in the direction of the arrow in said Fig. 7.

30 The present invention relates to electric car-signals, and has for its object to provide a signal for either one or the other or both cars approaching a common intersection between two sets of tracks or a curve at such 35 intersection, the purpose being to signal the car not having the right of way and allow the car having such right of way to pass on uninterrupted.

In detail the invention may be described 40 as follows:

Referring to the drawings, T T' represent the trolley or line wires of two intersecting systems of tracks.

45 P represents the pole to which my device is attached, said pole occupying a position preferably on one of the corners of the streets along which the cars travel. Mounted on the

50 pole at a convenient elevation from the ground is a box B, having secured therein in any convenient mechanical manner the solenoids S S', within which are adapted to gravitate freely the solenoid-bars 1 1', respectively, suspended from cables 2 2', passing through the top of the box and over guide-pulleys 3 3 55 3' 3', respectively, said pulleys being secured 60 to an arm A, projecting diagonally a suitable distance into the street. (See Fig. 1.) At the free end of the arm A are mounted the intersecting brackets or standards 4 4, from whose point of intersection there are secured arms 65 5 5, disposed in a plane at right angles to that of the arms formed by the intersection of the standards aforesaid. Pivoted at the ends of the arms formed by the intersection of the standards 4 are signal-arms 6 6, their short 70 ends being connected by a link 7, to which the upper end of the cable 2 is directly secured. To the ends of the arms 5 5 are pivoted the signal-arms 6' 6', whose short ends are connected by a link 7', to which the upper 75 end of the cable 2' is directly attached, the weight of the long ends of the respective arms permitting them to drop to their lowest position, thus causing the short ends to draw on the cables 2 2' and raise the solenoid-bars 1 1' 80 to their highest position within their respective solenoids.

Carried by the wires T T' for a considerable distance on each side of the point of intersection of said wires are signal-wires 8 8', 85 respectively, each wire leading to a resistance-coil R R' in the path of the current, by which the solenoids are energized, the opposite ends of the solenoids being grounded, as is obvious. The manner of coupling the 90 wires 8 8' to the wires T T' is best illustrated in Figs. 7 to 10, inclusive. Embracing the wire T (T') is a metallic sleeve 9, provided with a series of sockets 10, a corresponding sleeve 11, provided with a similar set of sockets 12, 95 being passed about the wire 8 (8'), each pair of sockets 10 12 being adapted to receive an insulating spacing-piece 13, by which perfect insulation is insured for the signal-wires under ordinary circumstances. The signal-wire 100 is disposed diagonally above the trolley-wire, (see Fig. 10,) so that as the trolley-wheel 14, carried by the pole 15, passes over the wire T (T') the signal-wire will contact with the

side wall of the groove formed in the wheel 14, the current conveyed by said trolley-wheel being partially deflected and caused to pass through the solenoid, which will be 5 then brought into electric connection at the time. The moment the current passes through the solenoid the magnetic force developed in consequence draws or attracts the solenoid-bar downward, this action lifting 10 the signal-arms, (see dotted position in Fig. 3 and full position in Fig. 4,) which thus serve as a signal or warning of the approach of the car having the right of way. Should both cars engage their respective signal-wires 15 at the same time, (which may sometimes occur,) both sets of signal-arms will be raised, thus giving the car not having the right of way a chance to come to a stop. The signal-arms are suitably painted to answer the purpose for which they are intended and at night 20 may be supplied with colored signal-lights.

Having described my invention, what I claim is—

An electric signal comprising two intersecting line-wires, a signal-wire carried by but in- 25

sulated from each line-wire, a solenoid in electric circuit with each signal-wire, a pole for the support of the solenoids, a solenoid-bar for each solenoid, cables for the support of the solenoid-bars, pulleys for guiding said cables, 30 suitable intersecting brackets forming a pair of arms disposed in one plane, a second pair of arms disposed in a plane at right angles to the first pair and having fixed ends secured at the point of intersection of said first pair, 35 signal-arms adapted to swing in planes at right angles to one another, pivoted to each of the aforesaid pair of arms, links connecting the adjacent ends of each pair of said signal-arms, the upper ends of the cables being 40 connected to said links, and the parts operating substantially as and for the purpose set forth.

In testimony whereof I affix my signature in presence of two witnesses.

CONRAD BUDKE, JR.
